(57) **CLAIM**

The ornamental design for a necklace, as shown and described.

DESCRIPTION

FIG. 1 is a front, top perspective view of a necklace, showing my new design;

FIG. 2 is a rear, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a front, top perspective view of the necklace in a detached state; and,

FIG. 10 is a rear, bottom perspective view of the necklace in a detached state.

The dashed broken lines in the figures are for the purposes of illustrating portions of the necklace that form no part of the claimed design.

The short-short-long dashed broken lines immediately adjacent to the claim area in the FIG. 10 are for the purposes of illustrating the boundaries of the necklace, and form no part of the claimed design.

1 Claim, 10 Drawing Sheets
